UNITED STATES PATENT OFFICE.

CHARLES C. WALLACE, OF ONEONTA, NEW YORK.

WHIP-SOCKET.

SPECIFICATION forming part of Letters Patent No. 613,402, dated November 1, 1898.

Application filed August 18, 1898. Serial No. 688,889. (No model.)

To all whom it may concern:

Be it known that I, CHARLES C. WALLACE, a citizen of the United States, residing at Oneonta, in the county of Otsego and State of New York, have invented certain new and useful Improvements in Whip-Sockets, of which the following is a full, clear, and exact description, such as will enable those skilled in the art to which it appertains to make and use the same, reference being had to the accompanying drawings, forming a part of this specification.

This invention relates to improvements in whip-sockets. It has for its object the provision of means for securing an inscription-bearing plate or card to a whip-socket.

It also has for its object the provision of means whereby the whip-socket can be secured to the dashboard of a vehicle.

The invention consists in the novel construction, combination, and arrangement of parts, such as will be hereinafter fully described, pointed out in the appended claims, and illustrated in the accompanying drawings.

In the accompanying drawings, Figure 1 is a side elevation showing a whip-socket embodying the invention. Fig. 2 is a similar view showing the edges of the clip. Fig. 3 is a sectional view on the line 3 3 of Fig. 1. Fig. 4 is a transverse vertical section.

In the drawings like reference characters designate corresponding parts.

The device consists, essentially, of the tube 1 and the clip 2. The tube is adapted to carry a whip and the clip serves to secure to the tube an inscription-bearing plate or card, and it also serves to secure the device to the dashboard of a vehicle. The tube is formed of sheet metal bent to the required shape. On its lower end is secured the perforated bottom 3. The latter serves to hold a whip in the socket, and by reason of the perforation extraneous matter introduced into the tube is allowed to escape.

In the wall of the tube, near its upper end, an annular rib 4 is formed. A hood 5 surrounds the tube and has its upper edge 6 turned inwardly to contact with the rib 4. The upper edge 6 is soldered to the annular rib, and the hood is thereby held in place. In the hood a recess 7 is formed for a purpose to be explained farther on.

The clip 2 has for the main part a cylindrical formation and surrounds the tube 1. It is formed of sheet metal suitably shaped. 55 The edges of the metal are turned to form flanges 8. In one of the flanges are the perforations 9 and in the other flange are the screw-threaded openings 10. Through the perforations 9 screws 11 pass and engage with the screw-threaded openings 10. By means of these screws the clip is clamped around the tube and thereby secured in place. When the clip is in place on the tube, the upper end of the same projects beneath the hood 5 and 65 the upper ends of the flanges 8 register with the recess 7. The hood serves to prevent moisture from passing downward between the upper end of the clip and the tube. The registration of the flanges with the recess 7 serves 70 to hold the clip and the tube in their proper relative positions. Upward movement of the tube in the clip is prevented by the projection 12 of the bottom 3. A downward movement of the tube is prevented by the hood. 75

A considerable part of the clip 2 is cut away to form the opening 14. Back of this opening and between the clip and the tube is a sheet of celluloid 15. Any other suitable transparent substance will serve the purpose. 80 Interposed between the sheet of celluloid and the tube is the inscription card or plate 16. The latter may have placed thereon any desired inscription.

In the upper end of the tube 1 is mounted 85 a rubber collar 17. The latter prevents the whip from rattling in the socket.

The whip-socket is secured in place by securing between the flanges 8 the edge of a dashboard, such as 18. The screws 11, passing through the flanges and the dashboard, firmly hold the whip-socket in place.

Having thus described my invention, what I claim, and desire to secure by Letters Patent, is—

1. In a whip-socket, the combination of a tube, a clip having an opening surrounding said tube, means for securing said clip in place on said tube, a transparent sheet interposed between said clip and said tube and over said opening, and an inscription-card inserted between said sheet and said tube. 95

2. In a whip-socket, the combination of a tube, a hood mounted on said tube, a clip hav-

ing an opening surrounding said tube and projecting into said hood, means for securing said clip in place on said tube, a transparent sheet interposed between said clip and said tube and over said opening, and an inscription-card inserted between said sheet and said tube.

3. In a whip-socket, the combination of a tube having an annular rib formed in the same near an end, a recessed hood surrounding said tube and having an inwardly-projecting flange secured to said rib, a clip having an opening therein surrounding said tube and projecting into said hood, flanges pro-

jecting from said clip and registering with the 15 recess in said hood, means for securing said flanges together, a transparent sheet interposed between said clip and said tube and over the opening in said clip, and an inscription-card inserted between said sheet and 20 said tube.

In testimony whereof I hereunto affix my signature in the presence of two witnesses.

CHARLES C. WALLACE.
